CLAIM

[22] Filed: **July 12, 1976**

The ornamental design for a combined pipe tamper and
scraper, as shown.

DESCRIPTION

FIG. 1 is a front elevational view of a combined pipe
tamper and scraper showing my new design;
FIG. 2 is a left side elevational view thereof;
FIG. 3 is a right side elevational view thereof; and
FIG. 4 is an isometric view thereof.
